United States Patent Office

Des. 193,874
Patented Oct. 16, 1962

193,874

JUG

Francis Blod, New Canaan, Conn., and George Stehl, New York, N.Y., assignors, by mesne assignments, to J. L. Prescott Company, Passaic, N.J., a corporation of New Jersey

Filed Mar. 20, 1961, Ser. No. 64,401

Term of patent 14 years

(Cl. D58—5)

FIG. 1

FIG. 2

FIG. 4

FIG. 5

FIG. 1 is a front perspective view of a jug showing our new design;

FIG. 2 is a rear perspective view thereof;

FIG. 3 is a side elevational view thereof;

FIG. 4 is a top plan view thereof; and

FIG. 5 is a top perspective view thereof on an enlarged scale.

The dominant features of our design reside in the portions shown in full lines.

We claim:

The ornamental design for a jug, as shown and described.
